(57) **CLAIM**

The ornamental design for a screen cleaner, as shown and described.

DESCRIPTION

FIG. 1 is a perspective view of a screen cleaner showing our new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof;

FIG. 7 is a bottom plan view thereof;

FIG. 8 is a perspective view of a screen cleaner in an open position showing our new design;

FIG. 9 is a front elevational view of the screen cleaner as shown in FIG. 8;

FIG. 10 is a rear elevational view of the screen cleaner as shown in FIG. 8;

FIG. 11 is a right side elevational view of the screen cleaner as shown in FIG. 8;

FIG. 12 is a left side elevational view of the screen cleaner as shown in FIG. 8;

FIG. 13 is a top plan view of the screen cleaner as shown in FIG. 8; and,

FIG. 14 is a bottom plan view of the screen cleaner as shown in FIG. 8.

The dotted lines throughout all the figures are intended to show features that are environmental only and form no part of the claimed design.

1 Claim, 8 Drawing Sheets
